Peter Brown
Chairwoman

UNITED STATES PATENT OFFICE.

PETER BROWN, OF CHICAGO, ILLINOIS, ASSIGNOR TO CHANNELL CHEMICAL COMPANY,
OF CHICAGO, ILLINOIS, A CORPORATION OF ILLINOIS.

MOP.

1,267,508.

Specification of Letters Patent.

Patented May 28, 1918.

Application filed January 9, 1915. Serial No. 1,350.

To all whom it may concern:

Be it known that I, PETER BROWN, a citizen of the United States, and a resident of the city of Chicago, in the county of Cook 5 and State of Illinois, have invented certain new and useful Improvements in Mops; and I do hereby declare that the following is a full, clear, and exact description of the same, reference being had to the accompanying 10 drawings, and to the numerals of reference marked thereon, which form a part of this specification.

This invention relates to an improved form of mop in which the mop fabric is 15 clamped to the mop head, the mop fabric being constructed with a supplementary tab which is held secured in the mop head, thus maintaining the two associated with one another.

20 It is an object therefore of this invention to construct a device comprising a sectional mop head, which, in assembled condition, clamps a supplementary tab of fabric associated with the mop fabric to hold said mop 25 fabric retained securely upon the mop head.

It is also an important object of this invention to construct a device wherein a plurality of plate members are constructed for attachment to one another to receive an 30 attaching tab of a mop fabric clamped therebetween to hold the mop secured upon the mop head.

It is also an important object of this invention to construct a device embracing 35 plate sections flanged outwardly and away from one another at their margins to afford a peripheral groove to receive a mop fabric engaged therein and with a portion of said mop fabric formed to extend inwardly between said plate sections and clamped therein to hold the mop fabric attached to the mop head.

It is furthermore an important object of 40 this invention to construct a device consisting of plates secured permanently or detachably to one another and flanged outwardly at their margins to receive a mop fabric engaged in the channel thus formed with a portion of the mop fabric clamped between 45 said plates and a handle socket member pivotally connected on the uppermost of said plates.

It is finally an object of this invention to construct an improved form of device of

oval shape, slightly pointed at each end to 55 facilitate projection thereof into places difficult of access for cleaning.

The invention (in a preferred form) is illustrated in the drawings and hereinafter more fully described.

In the drawings:

Figure 1 is a top plan view of a device embodying the principles of my invention.

Fig. 2 is a longitudinal central vertical section taken therethrough.

Fig. 3 is a transverse vertical section taken on line 3—3 of Fig. 2.

Fig. 4 is a top plan view of a mop fabric detached from the mop head.

Fig. 5 is a central vertical longitudinal 70 section taken therethrough.

Fig. 6 is an enlarged fragmentary detail taken on line 6—6 of Fig. 4.

Fig. 7 is a fragmentary detail section illustrating a modified means of attaching 75 the respective mop head plates one to another to permit detachment thereof.

As shown in the drawings:

The mop head itself consists of a pair of similarly constructed plates each denoted by 80 the respective reference numerals 1 and 2, and flanged outwardly away from one another, as indicated by the respective reference numerals 3 and 4, at their margins, to form a peripheral outwardly concave 85 groove when in assembled relation. Each of said plates adjacent the respective marginal flange thereon is struck downwardly as indicated by the reference numerals 5 and 6, respectively, affording a continuous groove on 90 the upper surface and a rib on the under surface of the respective plates, so that when said plates are assembled with one another, as clearly shown in Figs. 2 and 3, the rib 5, of the upper plate registers with the 95 groove 6, of the plate 2. Tongues 7, are struck upwardly from the upper plate 1, and pivotally connected thereto by means of rivets 8, is a handle socket member 9.

The mop fabric for attachment to the mop 100 head is a continuous closed loop and is provided with a tubular portion 10, adapted to lie within said outwardly concave groove formed by the flanges 3 and 4, of the mop head plates and stitched on the inner 105 periphery of said tubular portion of the mop fabric is a continuous tab of fabric 11. This tab 11, of the mop fabric, lies between

the plates 1 and 2, of the mop head, and is held securely therein due to the fact that said plates of the mop head are securely fastened to one another by means of rivets 5 12, and the respective interfitting members 5 and 6, of the mop head plates serve to grip said tab securely to prevent the mop being pulled away or disengaged from the mop head.

10 In the modified form of my invention illustrated in Fig. 7, I have shown releasable means for detachably connecting the respective mop head plates one to another to permit separating the same when it is desired to remove the mop fabric therefrom. For this purpose in place of the rivets 12, hereinbefore referred to, I employ threaded bolts 13, engaging through registering apertures in said respective mop head plates and 15 with a wing nut 14, threaded on the end of each bolt which, upon being tightened, serves to clamp the mop head plates tightly to one another.

15 The operation is thought to be obvious from the description. However, in attaching the mop fabric upon the mop head the tab of fabric 11, which is stitched to the upper portion of the mop fabric, is laid upon the plate 2, and the plate 1, is then secured thereover, thus clamping said tab of fabric securely between said plates. The upper portion of the mop fabric is of course engaged in the outwardly concave groove formed by the outwardly flaring flanges of 20 said respective plates. The modified method of connecting the mop head plates one to another is shown in Fig. 7, that is by means of a bolt and wing nut, permitting the respective mop head plates to be detached 25 from one another, thus permitting removal of the mop fabric for cleaning or repair, after which it may be again easily replaced in position. The peculiar shape of the mop fabric permits the same to be used in other- 30 wise inaccessible places with the utmost ease and convenience.

35 I am aware that various details of construction may be varied through a wide range without departing from the principles of this invention, and I therefore do not purpose limiting the patent granted otherwise than necessitated by the prior art.

I claim as my invention:

40 1. The combination with a continuous looped mop fabric having an attaching tab thereon, of a mop head comprising a pair of plates to receive said tab clamped therebetween to hold said mop fabric attached upon the mop head.

45 2. In a device of the class described the combination with a continuous looped mop

fabric, of a tab of fabric stitched to said mop fabric, a mop head comprising a plurality of plates adapted to be secured one to another with said fabric tab engaged therebetween to hold the mop fabric attached upon the mop head.

50 3. In a device of the class described a continuous looped mop fabric, and an attaching tab secured to the inner periphery thereof and projecting inwardly therefrom.

55 4. The combination with a continuous mop fabric having a tab thereon of a mop head comprising grooved upper and lower plates, the margins thereof flanged outwardly to afford an outwardly concave groove, and means securing said plates one to another with said tab engaged therebetween.

60 5. The combination with a mop fabric provided with a tab of similarly constructed flanged plates adapted to be connected one to another in parallel relation, and registering ribs and grooves on said respective plates inside of the flanged portions thereof and engaging said tab to hold the mop fabric in position against the flanges of the plates.

65 6. In a device of the class described the combination of a mop fabric having an attaching tab thereon of a mop head comprising an upper and lower plate, the margin of one flanged upwardly and outwardly, the lower plate adapted to be attached to said upper plate, the margin of said lower plate flanged downwardly, and together with the flange of the upper plate affording an outwardly concave groove, a rib struck downwardly on the under surface of said upper plate, said lower plate having a groove in the upper surface thereof adapted to register with said rib, and means connecting said plates one to another with the attaching tab therebetween.

70 7. In a device of the class described the combination of a mop fabric having an attaching tab thereon, of a mop head comprising a plurality of plates adapted to be connected one upon another with said tab disposed therebetween, and registering means on said respective plates adapted to engage the attaching tab of said mop fabric to hold the same securely retained and clamped between said plates.

75 In testimony whereof I have hereunto subscribed my name in the presence of two subscribing witnesses.

PETER BROWN.
